MOTION-PICTURE-PROJECTING MACHINE

Application filed July 11, 1925. Serial No. 42,947.

This invention relates to a motion picture projecting machine of novel and improved construction.

It is an object to provide a device of this character in which after projection has been completed the mechanism will automatically rewind the film and then repeat the projection,—this sequence of operation occurring as often as desired.

10 Another object is that of constructing a device of this type in which the rewinding phase of the cycle of operation occurs at greater effective speed than the projecting phase thereof.

15 Still another object is that of furnishing a machine in which, upon the projecting operation or phase being completed, a second apparatus will be set in operation, so that, if desired, this second apparatus will be actuated during the period of rewind of the first machine.

A further object is that of constructing a machine in which the strains to which the film is subjected will be reduced to a minimum, 25 so that the machine will operate over comparatively long periods of time without necessity of repair or renewal of the film due to breakage; and the apparatus, in addition to other uses, will be of particular value in connection with advertising, demonstrations by salesmen, etc.

30 A still further object is that of furnishing a projecting machine in which the parts will preferably operate in a virtually automatic manner, and in which these operations will be of a positive nature and will be accomplished by relatively simple mechanisms, so that the apparatus itself may be relied upon and may be utilized by persons relatively inexperienced in the operation of motion picture projecting machines.

An additional object is that of providing a device which will efficiently perform the purposes for which it is intended, and which 45 will also be economically and readily manufactured and easily assembled.

With these and further objects in mind, the invention accordingly comprises the features of construction, combination of elements 50 and arrangement of parts which will be exem-

plified in the construction hereinafter set forth, and the scope of the application of which will be indicated in the claims.

For a fuller understanding of the nature and objects of the invention reference should be had to the following detailed description taken in connection with the accompanying drawings, in which:

Fig. 1 is an elevation of the left side of the projecting machine and showing the film and 60 sprocket compartment;

Fig. 2 is a similar elevation of the right side of the machine and showing the operating mechanism thereof;

Fig. 3 is an enlarged sectional view taken 65 along the lines 3—3 of Fig. 2;

Fig. 4 is an enlarged fragmentary side view of certain of the operating mechanism as shown in Fig. 2;

Figs. 5 to 11 inclusive are views of certain 70 of the details of the operating mechanism;

Fig. 12 shows the wiring circuit involved;

Fig. 13 is a rear elevation of the gate; and

Fig. 14 is a sectional side view of the gate assembly and taken along the lines 14—14 75 of Fig. 13.

Referring primarily to Figs. 1 and 2, the numeral 15 indicates the casing of the apparatus, which, for the sake of portability, in the present exemplification is provided with a 80 handle 16. The interior of this casing is divided into two compartments by the use of a longitudinally-extending partition 17 preferably of fire-proof material, such as sheet metal. The first of these compartments houses 85 the film and sprocket mechanisms, while the second houses the electrical apparatus and the mechanism which serves to actuate the film reels, sprockets, etc.

Referring generally to the apparatus 90 housed within the first compartment, it will be observed that a pair of reel-shafts 18 and 19 extend through the partition 17 and that reels 20 and 21 respectively are fixed to these shafts. The first of these reels may, if desired, be enclosed within a case 22 formed with a slot 95 for the passage of the film strip 23, and this reel in the present embodiment is the one which receives the film during the projecting operation. The reel 21 receives the film dur- 100

ing the rewind operation, and if desired, a strip 24 may be provided adjacent the edge of this reel in order to guard against a displacement of the film, which is further prevented in both reels by the use of guards 25 which bear against the outermost convolutions of the film and are swingingly secured to the partition-member by the use of shafts 26 and 27, respectively.

10 In its passage between the reels the film traverses the various sprockets, guide-rollers, etc., which have been generally shown in Fig. 1. For example, following the film from the reel 21 it will be noted that the partition 17 carries a roller 28, under which the film passes, and immediately beyond this roller is a second roller 29, which is mounted upon an arm 30 bent to provide a shaft which extends through the partition and is connected upon the opposite side thereof to operate a disconnect switch in the event of film breakage. Thus, the film passes over a feed-sprocket 31, and subsequently through the gate 32 of the projector, this latter element being hereinafter more particularly described. Immediately 25 below the gate 32 is the intermittent sprocket 33, and subsequently to its passage over this latter element the film passes to a sprocket 34 corresponding to the sprocket 31, and 30 after passing over an idler roller 35 it moves into the casing 22 of the reel 20.

In order to project light images this compartment is also provided with a suitable lens assembly 36 extending through an opening in 35 the casing 15 and in line with the opening of the gate 32,—light being projected through the latter by means of a reflecting and condenser unit 37, which receives illumination, for example, from a bulb mounted in the mechanism compartment.

Referring to this apparatus compartment, it will primarily be observed that a bulb 38, as aforementioned, is mounted adjacent the opening in the partition 17 through which the unit 37 is visible, and obviously a reflector may be employed as in the usual construction in order to direct a maximum amount of the light rays through this opening. The lamp 38 is mounted in a socket 39, which, if desired, 50 is connected with a variable resistance 41 contained within a suitable housing 42 by means of leads 40, so that the brilliancy of the source of illumination may be regulated with nicety by means of the knob 43.

55 The entire apparatus is in the present instance driven by a motor 44, the power shaft 45 of which drives a belt 46 connected by means of a pulley 47 with what is termed primary drive-shaft 48, this shaft serving to 60 drive the reels and sprockets, as hereinafter brought out.

Referring primarily to the intermittent sprocket drive, it will be noted, as in Fig. 3, 65 that the shaft 48 has one of its ends supported within a frame 49 extending from the parti-

tion 17, and that this shaft carries a disk 50 which is fixedly mounted thereon, and which disk supports an inwardly-extending pin 51. A drum 52 is also carried by the shaft 48 and is rotatable with respect thereto. This drum, by means of a partition 53 is divided into two compartments, the outer of which encloses a hub 54 rotatably encircling the shaft 48, a spring 55 being coiled around this hub and having at least one of its ends extending through and beyond a slot 56 formed in the periphery of the drum body. The inner compartment of the drum houses a gear 57, which is slidably attached to the shaft 48, and this gear meshes with a gear 58 carried upon a stub-shaft (not shown) secured to the partition 53, the teeth of this gear in turn meshing with a gear 59 mounted upon a counter-shaft 60, to which latter a pin-carrying disk 61 forming one element of a Geneva movement is secured. The shaft 48 terminates at a point immediately beyond the gear 57, and a shaft 62 arranged in line with the end of the shaft 48 rotatably supports the drum 52 and carries at its outer end the intermittent sprocket 33, its body being rotatably supported by the partition 17. At its inner end, i. e., the end which extends into the drum, this latter shaft supports the "Maltese cross" of the Geneva movement, and has a socket, into which the male end of the shaft 48 extends.

Now with a view to obtaining a proper operation of the parts when the shaft 48 is driven, it will be noted that in the present exemplification a shifting-band 63 is rockingly attached to a bracket 64 secured to the main partition, as has been particularly shown in Figs. 2 and 4. This band carries guide-lugs or forks 65, which straddle the peripheral edge of the disk 50. As a consequence, if the band 63 is swung in the manner hereinafter brought out it will be obvious that the disk will be projected or retracted with the shaft 48, and, consequently, the pin 51 may be moved in relation to the spring 55 so that their paths of travel intersect. In addition to the lugs or forks the band 63 carries a stop-member 66, which is disposed in such a position that, when the band is shifted to a point at which the pin 51 carried by the disk 50 will not engage with the spring 55, this stop will be engageable with that end of the spring 55 which projects beyond the edge of the drum casing 52.

Thus, it will be appreciated that if the shaft 48 is driven by means of the pulley 47 this will result in a rotation of the disk 50. However, presuming that the parts are in the position illustrated in Fig. 3, and in view of the fact that the disk is not in a position at which the pin 51 carried thereby engages the spring, it will have no useful function. Due to the frictional engagement of the parts the drum 52 will, of course, tend to turn with the shaft 48, but this tendency will be in turn counter-

acted due to the fact that the end of a spring will engage the lug 66, thus holding the drum 52 stationary. As a consequence, the gear 57 will rotate with respect to the partition 53 which forms a part of the drum, and this rotation will result in a driving of the gears 58 and 59 and the shaft 60, thereby operating the pin-carrying disk 61 of the Geneva movement, which will result in an intermittent movement on the part of the shaft 62 and sprocket 33.

When, on the other hand, the band is shifted so that the guide-lugs 65 move the disk 50 inwardly it will be appreciated primarily that the lug 66 will move to a position beyond the end of the spring 55, and, as a consequence, the drum may be freely turned. The pin 51 will also be moved incident to such shifting so that it will travel in a path which will be interrupted by the spring. As a consequence, the pin will engage this element and the drum will be moved in synchronism with the disk. Under such conditions it will be apparent that no driving of the gear train will occur and that the Geneva movement will also not be actuated. Consequently, the shaft 62 will move in unison with the shaft 48, and the sprocket 33 will be driven at the same speed to continuously move the film at a corresponding rate.

Now with a view to driving the sprockets 31 and 34 it will be observed that the first of these sprockets is carried by a shaft 67, which is termed the secondary drive-shaft, and the second of these sprockets, as in Figs. 1 and 2, is mounted upon a shaft 68. These latter shafts carry sprocket gears 69 and 70, respectively, and at this time it will be noted that the drum 52 carries at its inner end, i. e., that end nearest the sprocket 33, a casing or runway 71, within which one portion 72 of a double gear is disposed, this gear being rotatably mounted upon a suitable bushing 73 which supports the shaft 62. The secondary portion of this gear, which is in the nature of a sprocket 74, extends beyond the casing or runway 71, and a chain or other suitable connecting element 75 passes around the sprocket gears 69, 70 and 74. It will furthermore be noted that the countershaft 60 will be continuously rotated so that the gear 74 will be correspondingly moved, which will in turn impart a simultaneous and corresponding movement to the sprockets 31 and 34. If, on the other hand, the disk 50 is coupled with the drum in the manner aforescribed the sprocket 74 will move in synchronism with the shaft 48, but such movement will be in a direction reverse to the movement aforescribed, and this movement will be at a much higher rate by virtue of the fact that no reduction drive is involved.

It will be understood that any desired mechanism may be employed for the purpose of driving the shutter (shown in dotted lines

at 148 in Fig. 2). For example, as has been indicated in this figure, as well as in Fig. 3, the shaft 48 may carry a gear 149 which meshes with the teeth of a gear 150 carried by the frame 49, and this gear in turn may mesh with a gear 151 suitably connected to the shutter, as in conventional construction.

Referring to the mechanism by means of which the reel shafts 18 and 19 are driven, it will be noted that the secondary drive shaft 67, as aforesigned, will be driven by the chain 75, and that this shaft supports a pair of opposed clutch elements 77 and 78. While these elements may take any desired form, it is preferred to have them embody a construction of the nature shown in Figs. 8 to 11, in which it will be noted that the clutch 77 consists of a ball-retaining member 79 and a wedging member 80, and that the clutch 78 consists of corresponding elements 81 and 82, respectively. Thus, the members 80 and 82, being secured to shaft 67, and with their wedging elements extending in opposite directions, it will be understood that one of these clutches will lock when the shaft 67 is rotated in clock-wise direction, while the second of the same will have lost motion, and if this shaft is rotated in counter-clockwise direction the second clutch will lock, while the first will have lost motion.

In order to connect these elements with the reel shafts it will be noted that in the present instance they are each provided with an annular peripheral groove 83, and resting one within each of these grooves are suitable connecting members 84 and 85. As in Fig. 2, the first of these members traverses an idler 86 and passes around a grooved pulley 87 affixed to the shaft 19. The second of these members likewise passes over an idler 88, and thence to a grooved pulley 89 affixed to the shaft 19.

Thus, during projection, and when the drum 52 is held against rotation, the shaft 18 and reel 20 will be driven to receive the film strip and to wind the same upon the reel 20. During the rewind operation, however, and when the drum moves with the shafts 48 and 62, the member 85 will not be driven, but the member 84 will be positively driven to correspondingly actuate the reel 21.

In the present instance, in order to positively shift the band and consequently effect a coupling of the drum with the shaft or a retention of the latter while permitting a driving of the former, a mechanism has been especially devised, which has been shown particularly in Figs. 2, 3 and 4. The actuating elements for this mechanism have been shown in Fig. 1. Referring primarily to the latter, it will be noted in the figure designated that the guard 25 associated with the reel 21 is extended as at 90 beyond the shaft 26. Adjacent this extension is a trigger 91 attached to a shaft 92, and an arm 93 is attached to a shaft 94 and carries a pin 95, which may

cooperate with the trigger 91 to prevent a turning of the shaft 94. The guard 25 which is associated with the reel 22 and carried by the shaft 27 has a pin-carrying arm 96, the pin of which rides in a slot 97 formed at the lower end of a link 98. The upper end of this link is attached to a trigger 99 having its opposite end supported by a shaft 100, an arm 101 being disposed adjacent this trigger and mounted upon a shaft 102; this arm carrying a pin 103 cooperable with the trigger 99 in order, in certain instances, to prevent a turning of the shaft 102.

With reference to the band-shifting mechanism, and also with a view to harmonizing the movements of the shafts 94 and 102, it will be noted, as in Figs. 2 and 3, that these shafts are extended through the partition 17. The first of these shafts carries at its outer end a crank 104, to the outer end of which a link 105 is attached; this link being secured to a crank arm 106 attached to the shaft 102. Thus, it will be appreciated—again referring to Fig. 1—that when, for example, the arm 93 is restrained against movement by means of the trigger 91 the arm 101 will be in a position at which its pin is free of the trigger 99, and a contrary condition of facts will exist when the trigger 91 is moved to its releasing position, it being obvious that the movements of the arms 95 and 101 will be synchronized by the coupling afforded by the link 105. Furthermore, it will be apparent that with an arrangement of parts similar to that shown in Fig. 1, which will occur during the projecting phase of the cycle of operation, the guard 25 associated with the reel 21 will gradually have its outer end swing downwardly as the film upon this reel is passed to the reel 20. When merely a certain minimum of film is left upon the reel 21 the trigger 91 will be thrown to released position by being engaged by the arm 90. This will release the pin 95 of the arm 93 and permit the latter to swing, and upon this action occurring it is obvious that the arm 101 will be swung to a position at which its pin 103 will be engaged by the trigger 99. Conversely, assuming that the rewind phase of the machine is occurring the guard 25 associated with the reel 20 will swing inwardly as the film passes from this latter reel to the reel 21. Through such swinging the pin 103 will be engaged by the trigger 99, while the pin 95 of the arm 93 will be out of contact with the trigger 91. During the major portion of the inward travel of the last mentioned guard 25 the trigger 99 will not be actuated, due to the pin-and-slot connection extant at 97. However, after all film short of a certain minimum has been exhausted from the reel 20 the trigger 99 will be actuated to release the arm 101, and, consequently, permit the latter to move to the position shown in Fig. 1, which will obviously result in the arm 95 again assuming the position also shown in this figure.

The shifting of the band 63 is accomplished in the present instance by securing a cam 107 to the shaft 102 and providing a guide 108 upon the band with which this cam cooperates. Thus, in the position shown in Fig. 2, in which the parts are set for projection, the cam will have shifted the band to a position at which the disk 50 has its pin 51 out of engagement with the spring carried by the drum. It is obvious, however, that if the drum is moved to a position at which it will release the pin 95, and if the arm 93 is swung to correspondingly move the shaft 94 the link 105 will be moved to the position shown in Fig. 4, and the cam will also be shifted to the position indicated in this figure, in which position the disk is coupled with the drum in order to rotate the same.

With a view to providing a potentialized element serving to effect a positive shifting of the parts when one or the other of the triggers has been released it will be noted, particularly as in Fig. 3, that the shaft 94 rotatably supports a gear 109, to which a disk 110 is coupled. This disk is provided with an outwardly-extending arm 111, to which one end of a spring 112 is attached, the opposite end of this spring being attached to an extension 113 forming a part of the crank 104 and extending upon the opposite side of the shaft 94. It will be obvious that if the spring is under tension, as in Fig. 2, and upon the trigger 91 being released, the arm 104, and consequently the link 105, will be positively shifted thereby, and if the spring is again tensioned it will be apparent that subsequently, and upon the trigger 99 being actuated, the spring will again serve to shift the link 105,—and in this instance back to the position shown in Fig. 1.

With a view to automatically effecting such tensioning of the spring it will be noted that the secondary drive-shaft, i. e., the shaft 67, carries a gear 114 fixedly secured thereto. As a consequence, this gear will be positively rotated in clockwise or counterclockwise direction, according to the direction of rotation of this shaft. A countershaft 115 is secured to the partition 17 and in a position between shafts 67 and 94. This shaft carries a gear, the teeth of which mesh both with gears 114 and 109 so that motion is transmitted from the former to the latter. With reference to the construction of the gear positioned upon the shaft 115, attention is particularly invited to Figs. 3, 4 and 7. In these views it will be noted that this gear includes a hollow body 116 formed with an annular series of teeth 117. This series of teeth is interrupted by peripheral openings 118 which afford communication with the interior of the gear body. Positioned within this body is a pair of oppositely-extending 125

pawl-members 119, which are pressed in opposite directions by a spring 120, and the ends of these pawl-members terminate in teeth 121, which correspond to the teeth of the series 117.

5 Conceding that the trigger 91 has just been thrown, and that the spring 112 has actuated the link 105 in the manner aforescribed, it will be obvious that the direction of movement of the shaft 67 will be reversed. As a consequence of such reversal the gear 114 will engage one of the teeth 121 and tend to swing the same outwardly, which will be prevented. Thus, the gear body 116 will be turned, and the gear 114 will engage the series of teeth 117 and continue the rotation of the body 115 until such time as it engages with the tooth 121 of the second pawl-member, in which position it will override this tooth, and, consequently, the gear 115 will not be turned any further. Due to the fact that the disk 110 is coupled to the gear 109, this disk will also be turned, for the reason that during the partial rotation of the body 116 the gear 109 will be driven. This action of the parts will serve to potentialize the spring, and upon the trigger being released it will be apparent that the spring will serve to effect a shifting of the band, and, consequently, the disk. 30 Incident to such shifting, however, the direction of drive of the shaft 67 will again be reversed, which will obviously cause the gear 114 to again swing the gear body 116, due to the fact that it will not continue to override the tooth 121 of the second pawl-member, but will rather tend to force the same outwardly. The gear 115 will now again be turned to correspondingly move the gear 109 until the teeth of the gear 114 reach a position at which they engage the second pawl-member, where again they will override this part.

In addition to shifting the band, the link 105, when actuated, serves to throw a two-way switch 122 to one of its extreme positions. In one of these positions, and as has been shown in Fig. 12, it serves to close the circuit through leads 123 of the bulb 38. This, of course, will occur during the projecting phase of the cycle. In its other position the switch discontinues the circuit through the leads 124, these latter leads being connected, if desired, with a second projecting machine, an electric bulb, a stereopticon machine, or any other desired element, so that the latter will be actuated during the rewind operation of the machine just described.

The movements of the disk 110 are limited 60 preferably by the use of a stop-pin 125 secured to the partition and engageable with shoulders 126 formed in the edge of the disk. These shoulders also act as cam surfaces to actuate a switch 127, which, when open, 65 serves to connect the motor 44 with a source

of energy (not shown), but with which the leads 128 are connected. This connection is established through a variable resistance 129 controlled by a knob 130, so that the speed of the motor may be regulated during the projecting phase of the operation. When closed, the switch 127 bridges across a certain amount of the resistance 129 in order to supply a greater amount of current to the motor during the rewind operation, which is desirable due to the higher rate of speed at which the film is moved, and, consequently, the greater resistance offered by the operation of the parts. 75

The arm 30, as aforesated, is operatively coupled with a disconnect switch, which has been shown at 131, and in the event of film breakage, and this switch opening the circuit, the parts may, nevertheless, be operated by a cut-in switch 132. The switches 133 and 134 control, respectively, the bulb 38 and motor 44, and if during projection it may for some reason be desired to energize, for example, the source of illumination connected with the leads 124, this may be accomplished 90 by the use of a cut-in switch 135.

Finally, with reference to the gate mechanism, which has been generally indicated at 32, attention is primarily invited to Figs. 13 and 14 in which it will be observed that this member may include an arm 136, which is rockingly attached to the outer end of a shaft 137. A bracket 138 is secured to this arm and extends upwardly and adjacent the inner end of the shaft 137, at which point it rockingly encircles the latter. A plate 139 is disposed adjacent the arm 136 and has its outer end encircling the shaft 137 at points between the arm and bracket. The plate is formed with a framing opening a window 140 and has a lug 141 extending outwardly from its body and beyond the outer edge of the arm, this lug being engaged by a spring 142 carried by the bracket. Adjacent its lower end the arm 136 is enlarged as at 143, and at this point it supports a plate 144 which is curved to conform to the contour of the sprocket 33 and is grooved to accommodate the teeth of the latter. While the connection between the plate 144 and the enlargement of the arm 110 115 may be established in any desired manner, it is preferred that a spring 145 be utilized for this purpose. 100

Thus, it will be obvious that the elements of the gate turn substantially as one unit 120 around the shaft 137. With the film in position it will be understood that the arm 136 may be swung inwardly, and in such movement will carry with it the plate 139, which will come to lie with its inner face adjacent 125 the outer face of the film, in which position the framing opening 140 will be in line with the light opening of the projecting machine, as has been shown in Fig. 14. A continuing inward movement of the arm will result in the 130

plate 144 yieldingly pressing the film against the periphery of the sprocket 33, and it will here be noted that incident to the lug 141 and spring 142 a similar pressing action will occur between the plate 139 and the film strip. Obviously, the gate may be retained in this position in any desired manner, for example, by the use of a pin 146 which rides against a spring 147, thus affording a catch for the parts. With a construction of this nature, in addition to the simplicity of the gate and the fact that all of its parts are supported by a common shaft, and that a portion thereof serves to prevent displacement of the film from the intermittent sprocket, the loop will at all times be maintained, as will readily be apparent.

Reviewing the operation of this machine, it will be understood that the film is placed upon the reel 21 and its ends threaded around the various rollers and sprockets, care being taken to establish loops in advance, and to the rear, of the intermittent sprocket 33. The end of the film is coiled around the reel 20 and the machine is now ready for operation. Such operation can be secured by closing the switches 133 and 134, which will energize both the bulb 38 and the motor 44, thus driving the sprocket 33 intermittently and the sprockets 31 and 34 constantly, and also driving the reel 20 constantly. The operation may be discontinued at any time by simply opening the switches last referred to, but if they are maintained in closed position the operation will continue until reel 20 has received virtually all the film and the quantity of film upon the reel 21 has been reduced to a minimum. Upon this condition prevailing the guard 25 would have swung to the position at which the trigger 91 is actuated so as to release the arm 93, swing the arm 101 to a position at which it is engaged by the trigger 99 and actuate the link 105 to not alone operate the switch 122 to discontinue the energization of the bulb 38, but also to close the switch 127 to pass more current through the motor 44. In addition to this operation the disk 50 will have shifted to a position at which it is coupled with the drum, and, consequently, the film begins to rewind and at a much higher rate of speed than that at which projection occurred. Current will not pass through the leads 124 for the purpose aforesaid, and at the initial stages of the rewind operation the spring 112 will again be potentialized, as has been aforescribed. This rewind will continue until the guard 25 actuates the trigger 99, thus permitting the arm 101 to shift, which will result in a disconnecting of the disk from the drum to again continue the projecting operation, and this operation will also result in the switch 127 being opened, the switch 122 being thrown to discontinue the current through the leads 124 and to also cause the bulb 38 to be ener-

gized. During this reversal the film loop will be maintained, and it will be obvious that if any film breakage should occur, resulting in an operation of the disconnect switch 131, the other switches may be actuated to effect the results desired.

Thus, among others, the objects mentioned are accomplished, and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A motion picture projecting machine, including, in combination, a pair of shafts, film-engaging means associated with one of the same, a source of power connected with the second shaft to turn the same constantly in one direction, an intermittent mechanism to translate the movement of the last-named shaft into periodic movement on the part of the first-named shaft, a housing for said mechanism and forming a part thereof, means for retaining said housing and parts of said mechanism substantially stationary during the projecting phase of the machine, and means for rotating said housing in substantial unison with said last-named shaft during the rewind phase of the machine whereby to render said mechanism inoperative and to drive said shafts in unison.

2. A motion picture projecting machine, including, in combination, a pair of shafts, a source of power connected with one of the same to constantly drive it in one direction, film-feeding mechanism connected with the second of said shafts, intermittent mechanism including a pair of members, one connected with said latter shaft and the other connected with said first-named shaft, a housing supporting one of said members, means for retaining said housing substantially stationary during one phase of operation of the machine to periodically actuate said film-feeding means and in a direction reversed with respect to said first-named shaft, and means for coupling said housing with said first-named shaft to drive the same in unison therewith whereby to render said intermittent mechanism inoperative during another phase of operation of said machine, and to drive said film-feeding means constantly and in a

direction reverse to its first direction of movement.

3. A motion picture projecting machine, including, in combination, a pair of reels, a film-engaging sprocket between said reels, means associated with one of said reels for automatically operating said sprocket intermittently in one direction and constantly in another direction, and means bearing against the surface of the film upon said reels and shifted according to the thickness of the film body thereon for automatically controlling said last-named means.

4. A motion picture projecting machine, including, in combination, a pair of reels, a film-engaging sprocket between said reels, means associated with one of said reels for automatically operating said sprocket intermittently in one direction and constantly in another direction, means bearing against the surface of the film upon said reels and shifted according to the thickness of the film body thereon for automatically controlling said last-named means, and means for potentializing said latter means.

5. A motion picture projecting machine, including, in combination, an intermittently-operated sprocket, means for supporting the film, and a gate disposed adjacent said sprocket, said gate including a plate formed with a window, an arm disposed adjacent said plate, a resilient connection between said arm and plate, a shaft supporting both of the same, said film passing adjacent said plate and in line with the window of the same, and a further plate carried by said arm and bearing against said film in order to press the same into operative contact with said sprocket.

40 6. A motion picture projecting machine, including, in combination, an intermittently-operated sprocket, means for supporting the film, and a gate disposed adjacent said sprocket, said gate including a plate formed with a window, an arm disposed adjacent said plate, a resilient connection between said arm and plate, a shaft supporting both of the same, said film passing adjacent said plate and in line with the window of the same, a second plate, and means for yieldingly connecting said latter plate with said arm, said plate lying adjacent said sprocket and pressing said film into operative engagement therewith.

55 In testimony whereof I affix my signature.
ORAZIO J. ANTONELLI.
